UNITED STATES PATENT OFFICE.

ROBERT J. STOKES, OF TRENTON, NEW JERSEY, ASSIGNOR TO THERMOID RUBBER COMPANY, OF HAMILTON TOWNSHIP, NEW JERSEY, A CORPORATION OF NEW JERSEY.

DISK FOR FLEXIBLE COUPLINGS.

1,409,611.

Specification of Letters Patent. Patented Mar. 14, 1922.

Application filed September 23, 1921. Serial No. 502,737.

To all whom it may concern:

Be it known that I, ROBERT J. STOKES, a citizen of the United States, residing in Trenton, Mercer County, New Jersey, have 5 invented certain Improvements in Disks for Flexible Couplings, of which the following is a specification.

The object of this invention is to make a disk of a number of plies of fabric and vul- 10 canizable material, the plies of the disk being gradually reduced in width from the center to the surface and being so arranged that the disk will have the greatest thickness in line with the bolt holes.

15 The invention also relates to other details hereinafter described.

In the accompanying drawings:

Fig. 1 is a side view of the disk made in accordance with my invention;

20 Fig. 2 is an edge view;

Fig. 3 is a sectional view on the line 3—3, Fig. 1;

25 Fig. 4 is a side view showing the different plies of the disk, one upon another, the outer covering being removed;

Fig. 5 is a sectional view on the line 5—5, Fig. 4;

30 Fig. 6 is a view showing the different plies of the disk separated so as to illustrate the invention more clearly.

Fig. 7 is a sectional view of a flexible coupling illustrating my invention;

Fig. 8 is an end view of the coupling;

35 Fig. 9 is a perspective view of one of the washers;

Fig. 10 is a view showing a corrugated washer located between two disks;

Fig. 11 is a view of my improved disks as- 40 sembled with an ordinary disk; and

Fig. 12 is a view showing a ribbed washer.

The flexible disk 3 consists of a series of 45 layers of fabric combined with rubber, or other vulcanizable material. The disk is preferably made in two parts, which are ce- 50 mmented together by vulcanizable material as in Fig. 3. Each half consists of a base 4 of several layers of fabric made in the form of a ring and having an open center 5, as shown in Fig. 6. The different layers 6, 7, 8, 9 and 10 are mounted one upon another and on the base 4 as shown in Figs. 5 and 6. The rings formed of the different plies of material are narrower at the outer side than at the base.

55 The two rings are built up, as shown in

Fig. 5, and are arranged back to back, as shown in Fig. 3, and a covering 11, of fabric, is placed on each side of the disk, enclosing the several layers. The disk is then vul- 60 canized under pressure so as to make a uni- tary structure, such as illustrated in Figs. 1 and 2. The disk is perforated at 12 for the securing bolts, the perforations being through the thickest part of the disk so that the strain, to which the disk is subjected, is 65 taken by the thickest part of the disk.

This construction makes a very substantial disk, yet one which will yield under twisting strains, owing to the fact that it is comparatively narrow at the points between 70 the bolt holes, while on the line of the transmitting strains the disk is exceedingly substantial.

When the disk is mounted between the two parts 15 and 16 of a coupling, as shown in 75 Figs. 7 and 8, washers 13, Fig. 9 are preferably used, in which the flanges 14 are bent to conform to the shape of the disk, so that when the nuts are drawn on the bolt 17, the disk is firmly clamped between the washers. 80 The washers are preferably tapered as shown in Figs. 8 and 9 and they may be ribbed as shown in Fig. 12, in some instances the ribs being imbedded in the material when the bolts are tightened.

In some instances, a corrugated washer may be located between the two sections of the disks as shown in Fig. 10, if found desirable.

I claim—

1. A flexible disk used in couplings, said disk consisting of a series of layers of fabric and vulcanizable material, vulcanized under pressure, the fabric being in the form of rings differing in width from a common 95 centre line of stress.

2. A flexible disk, used in couplings, hav- 100 ing a central opening said disk being made of a series of plies of fabric and vulcanizable material, said disk having a series of bolt holes and being thicker on the line of stress than at the periphery or at the central opening.

3. A flexible disk used in couplings, said disk consisting of a series of layers of fabric 105 and vulcanizable material vulcanized under pressure, said disk being made of a series of rings of fabric placed one upon another, the rings at the center being of a greater width than at the sides.

- 2
4. A disk for flexible couplings consisting of a series of layers of fabric combined with vulcanizable material vulcanized under pressure, the layers of fabric being in the form of rings, the rings, at the center of the fabric, being wider than those at the periphery; and a series of bolt openings in the ring at the thickest point, the disk tapering towards the center and the periphery from the bolt holes.
5. A disk for flexible couplings consisting of a series of layers of fabric combined with vulcanizable material vulcanized under pressure, the layers of fabric being in the form of rings, the rings, at the center of the
- 10 fabric, being wider than those at the periphery, a series of bolt openings in the ring at the thickest point, the disk tapering towards the center at the periphery from the bolt holes; and an enclosing covering on each side of the disk, the whole being vulcanized to form a unitary structure.
- 15 6. The combination in a flexible coupling, of a flexible disk in the form of a ring having tapered sides; two spiders; each spider having arms; bolts securing the arms to the flexible disk; and washers, on the bolts, having flanges conforming to the tapered sides of the disk.

ROBERT J. STOKES.
